BERNARD MORGAN, OF KEENE, NEW HAMPSHIRE.

CUTTING-DIE AND METHOD OF MAKING THE SAME.

1,315,030.

Specification of Letters Patent. Patented Sept. 2, 1919.

Application filed December 24, 1917. Serial No. 208,564.

To all whom it may concern:

Be it known that I, BERNARD MORGAN, a subject of the British Empire, residing at Keene, New Hampshire, in the county of 5 Cheshire, State of New Hampshire, have invented certain new and useful Improvements in Cutting-Dies and Methods of Making the Same; and I do hereby declare the following to be a full, clear, and exact description of the invention, such as will enable others skilled in the art to which it appertains to make and use the same.

This invention relates to improvements in thread cutting dies and method of making 15 the same, and has for its principal object to provide a method of manufacture and design of die whereby the quantity of material used for the die and the labor required for its manufacture may both be materially reduced with a consequent large saving in 20 manufacturing cost.

It is well known that high speed steel is far superior to other kinds of steels for machine tools but it has heretofore been used 25 but little for the manufacture of thread cutting dies, because of its excessive cost, but by my improved method and design the cost is very little if any more than for dies of prior designs made of ordinary steel.

30 A further object of my invention is to provide a die of improved design possessing several important advantages over dies of existing types.

My improved die consists essentially of a 35 sheet metal disk or ring with the thread cutters projecting from the edge of the ring and shaped from the metal of the ring in such manner that the length of the cutter is not determined by the thickness of the metal 40 as in ordinary dies but instead the cutters may be as long as necessary with the thinnest metal having sufficient tensile strength for the purpose.

One advantage of my improved die is that 45 more cutting edges may be provided than have heretofore been employed. Another important advantage is that the die is self-clearing, that is, the cutting edges when rotated in the direction of the cut tend to bite 50 into the work, but when rotated in the reverse direction the cutting edges tend to release themselves with the result that the die may be screwed off the thread without wearing the thread down and distorting it, as 55 frequently happens with ordinary dies, particularly in cutting threads on soft metals.

Another important advantage of my improved die is that the cutters may be integral with a continuous supporting ring and yet so arranged that they may be adjusted 60 toward the center to compensate for the wear of the cutting edges.

In the accompanying drawings, I have disclosed two types of my improved die and also the important steps in its process of 65 manufacture, and in said drawings—

Figure 1 is a plan view showing the punched blank from which a die for external threads is formed;

Fig. 2 is a view similar to Fig. 1, showing 70 the die after formation of the cutters thereon;

Fig. 3 is an enlarged view of portion of Fig. 2 showing the cutters in greater detail and also illustrating the method of adjusting 75 the cutters to compensate for wear;

Fig. 4 is a vertical section of the die on the same scale as Fig. 3;

Fig. 5 is a perspective view of the completed die; 80

Fig. 6 is a perspective view of a tap designed for internal threads; and

Fig. 7 is a detail view of a modified construction.

The blanks for forming dies for external 85 threads are cut from sheets of suitable steel by an ordinary punch press to the shape shown in Fig. 1, that is, the cut blank consists of an outer ring 2 of a diameter to fit the chuck or stock in which it is to be used 90 and a number of tongues 4 projecting from the inner edge of the ring. The ring may also be formed with several spaced holes 3 for locking it against rotation in the chuck or holder, or it may be held in the same manner as heretofore employed for ordinary dies. The tongues 4 are of a width equal to the desired length of the cutting edge and extend toward the center to a point somewhat greater than the radius of the thread 95 which they are designed to cut. In the drawing six tongues are shown but the number may, of course, be varied more or less.

After the blank is cut and before the metal is tempered, the tongues 4 are individually twisted to bring their inner edges into a plane approximately at right angles to the face of the ring. At the same time the edges of the tongues are shifted somewhat "off center" or forward against the 100 rotation or cut, all in the same direction, the shifting of the tongues off center being 105

preferably accomplished at the same operation as the twisting of the tongues. The degree to which the tongues are shifted may be varied more or less as experience determines. Both operations may be performed by a shaping press, the final position of the tongues being such that one edge of the end face of each tongue coincides approximately with the radial line through the center of the base of the tongue as indicated in Fig. 3, wherein the radial center line is shown at *c c*.

After the tongues are twisted to the proper position they will be cut to form the usual thread cutting teeth, that is, their ends will be serrated with each serration from one side to the other slightly more projected than the next serration and with the edges of the serrations inclined somewhat from the circumferential so that the corners of the teeth on the advancing edge of the cutters will bite into the metal when the die is rotated in the direction of the arrow in Fig. 3.

The teeth will usually be cut in the edges of tongues after the twisting operation but before the metal is tempered. This order of the steps is not, however, essential, as the teeth may be cut before the twisting or after the twisting and tempering.

In operation the die will be rotated in the direction of the arrow in Fig. 3, with the corners of the teeth marked *d* acting as the cutting edges so that the line of thrust from the cutting edge to the supporting ring will be off center as indicated by the dotted line *e e*. The effect of this is to cause the tongues which are somewhat elastic, to tend to straighten toward the radial and enter the metal. On the reverse direction of rotation, as the die is unscrewed, the tongues tend to bend toward the ring and away from the center so that the die unscrews without distorting the previously cut threads.

As the cutting edges wear away the increasing circumference may be compensated for by slightly straightening the tongues as shown in Fig. 3. A bar 7 of proper width is inserted between the teeth with one edge against the base at the rear edge of one tongue and its opposite edge near the outer end of the adjacent tongue. By twisting the bar in the direction shown, the tooth will be forced back or slightly straightened to thereby reduce the distance between the opposite cutters, and cause the teeth to enter deeper into the metal.

Thread cutting dies of the common type are made by cutting from a bar or rod of rolled steel a piece equal to the length of the cutters, and machining into shape with the teeth running circumferentially of the rod. In a rolled steel bar the grain of the metal extends longitudinally of the bar, so

that the teeth of the die are cut across the grain of the metal and are consequently materially weaker than if extending with the grain. Further, it is well known that the metal of the central section is inferior in strength and toughness to the metal near the surface, and in shaping the dies from the rod section the teeth come in the worst part of the metal and it is usual to find most threading dies, after a very little use, with one or more teeth broken. In sheet steel the surface or skin portion is always the tough or strong metal and in my improved design the cutting edges are directly on such surface.

In Fig. 7 I have illustrated a simple method of making a die adjustable to take up wear or accommodate slight variations in the diameter of the work to be threaded. As here shown, the ring 2 is provided with a tapered hole 15 at one point in its periphery and is then cut radially across the hole as indicated at 16, forming an expandable ring similar to the split ring of a clutch.

In supporting this ring in a chuck a screw terminating in a tapered pin will be threaded in the chuck with its axis parallel with the axis of rotation of the die and arranged so as to be forced against the tapered hole 15 when the die is held in the chuck. The pin will be initially set in sufficiently to expand the ring so that as the teeth wear the pin may be slightly retracted, allowing the ring to contract and thus reduce the diameter of the cutting edges to compensate for the wear. By this means a quicker adjustment of the cutters may be had than can be effected by springing each individual cutter in the manner above described.

In describing my improved die, I have stated that the ends of the cutters were twisted through approximately a quarter turn and that the teeth extended in substantially the plane of the annulus. It will of course be understood that it is not essential that either of these angles be exact. The extent of the twist of the cutters may vary considerably so long as the teeth are cut with the proper angle to the axis of rotation to give the desired pitch to the thread. That is to say, it is not necessary that the teeth be at a definite angle to the faces of the twisted ends of the cutters. The teeth may extend at a greater or less angle than the angle or pitch of the thread without affecting the operation of the cutter. In the same way, the teeth need not be at the exact angle of the pitch of the thread to the plane of the annulus, as the annulus may itself be clamped in the chuck at an angle to the axis of rotation.

It is of course desirable, however, that the teeth be cut at an angle to the annulus equal to the pitch of the thread so that the an-

nulus may be clamped in the chuck in a plane normal to the axis of rotation.

Dies or taps for internal threads may also be made according to my invention. Such a die is shown in Fig. 6 and comprises a middle disk or body portion 10 having tongues 11 projecting from its edge. The tongues are twisted in the manner shown to bring the outer ends of the tongues transverse to the plane of the disk and offset from the radial in the same manner as the cutters of the die for cutting external threads. The end faces of the tongues are provided with the usual serrations or thread-cutting teeth 12 shaped to cut when the die is rotated in the direction of the arrow and to release when rotated in the opposite direction.

The body 10 will be provided with a suitable opening 13 by means of which it may be attached to the cutter head, or any other usual or suitable means may be provided for the purpose.

The cutters of this type of die may be adjusted or "set" from time to time to compensate for wear in the same manner as the cutters of the other die.

It is, of course, understood that my invention is not limited to the details of design shown and described herein, for, so far as I am aware, I am the first to devise a die and a method of manufacture therefor whereby high speed steel or sheet material of any kind, may be used for the metal of the die with the attendant advantages above enumerated.

I claim:

1. The method of making a thread cutting die which consists in cutting from a sheet of steel a die member having flat cutter forming projections and then turning or twisting said projections to bring their flat faces approximately transverse of the plane of the sheet.

2. The method of making a thread cutting die which consists in cutting from a sheet of steel a die member having flat cutter

forming projections and then turning or twisting said projections to bring their flat faces approximately transverse of the plane of the sheet, thereafter tempering said projections to form cutting edges. 50

3. The method of forming a thread cutting die which consists in cutting from a metal sheet an annular die member having flat cutter forming projections extending 55 radially thereof and thereafter twisting said projections through approximately a quarter turn and forming serrations or thread cutting teeth in said projections with the serrations extending parallel with the plane 60 of the sheet.

4. A thread cutting die comprising an annular body portion of sheet metal, thread cutters extending radially of said body portion, each projection comprising a base integral 65 with the annulus and a cutting edge turned at approximately right angles to the base.

5. A thread cutting die comprising an annular body portion of sheet metal, thread 70 cutters extending radially of said body portion, each projection comprising a base integral with the annulus, and a cutting edge turned approximately at right angles to the base and offset radially so that the radial line 75 passing through the middle of the base lies to one side of the middle of the cutting edge.

6. A thread cutting die consisting of an annulus of sheet steel with the plane of the sheet intersecting the center of the annulus, 80 a series of cutters projecting radially within said annulus, each cutter having its base portion integral with said annulus and its free end turned at right angles to the base portion, and provided with thread cutting 85 teeth or serrations approximately parallel with the plane of the annulus whereby the length of the cutters is determined by the width of the projection.

In testimony whereof I affix my signature. 90

BERNARD MORGAN.
